AIR DIVERTER IN A VEHICLE HEATING SYSTEM

Klaus Frederick Nowak, Etobicoke, Ontario, Canada

Application December 18, 1958, Serial No. 53,811

Term of patent 3½ years

(Cl. D14—6)

Figure 1 is a perspective view of my new design for an air diverter in a vehicle heating system;

Figure 2 is a side elevational view of the air diverter of Figure 1; and

Figure 3 is an end elevational view of the air diverter of Figure 1.

The essential features of my design reside in those portions shown in full lines.

I claim:

The ornamental design for an air diverter in a vehicle heating system, substantially as shown and described.
